UNITED STATES PATENT OFFICE.

MATTHEW H. SLOAN, OF CUMBERLAND, MARYLAND, ASSIGNOR TO THE POTOMAC GLASS COMPANY, OF CUMBERLAND, MARYLAND, A CORPORATION OF MARYLAND.

DESIGN FOR A DRINKING VESSEL OR SIMILAR ARTICLE.

42,113.

Specification for Design.

Patented Jan. 23, 1912.

Application filed September 20, 1911. Serial No. 650,472. Term of patent 14 years.

To all whom it may concern:

Be it known that I, MATTHEW H. SLOAN, a citizen of the United States, and residing at Cumberland, in the county of Allegany and State of Maryland, have invented a certain new, original, and ornamental Design for a Drinking Vessel or Similar Article, shown in the accompanying drawing, which is a view in perspective of the same.

I claim:—

The ornamental design for a drinking vessel or similar article, as shown.

MATTHEW H. SLOAN.
